WIND BOX FOR SINTERING MACHINES

Charles H. Harris, San Luis Potosi, Mexico, assignor to American Smelting and Refining Company, New York, N. Y., a corporation of New Jersey

Application June 10, 1941, Serial No. 397,381

3 Claims.

(Cl. 266—15)

This apparatus relates to windboxes for sintering machines and particularly concerns windboxes of the type in which a pool of water is maintained in the lowermost portion of the windbox.

In operating a sintering machine of the down-draft type, it is necessary to clean out the windbox at intervals by reason of the accumulation of dust particles, and the like, originating from the charge and which are drawn through the grates of the machine into the windbox. In many operations, it has been proposed to maintain a pool of water in the bottom of the windbox and to collect therein, the non-gaseous materials passing through the grate bars into the windbox. An illustration of the latter practise is to be found in U. S. Patent No. 1,954,951 granted to Ronald C. Rutherford on April 17, 1934.

However, whether water be used in the windbox or not, it is normally necessary to shut down the operation of the sintering machine when cleaning the windbox of accumulated materials. This is due to the fact that entrance into the windbox is usually through doors in the side of the windbox and when they are opened, the draft on the charge is destroyed.

The present invention provides an improved windbox construction in which a pool of water is maintained within the windbox and from which the materials accumulating therein may be readily removed at any time without adversely affecting the normal draft on the machine.

Although the novel features which are believed to be characteristic of this invention will be particularly pointed out in the claims appended here-to, the invention itself, as to its objects and advantages, and the manner in which it may be carried out, may be better understood by referring to the following description taken in connection with the accompanying drawing forming a part thereof, in which

Fig. 1 is a side view, with parts broken away, of a section of a sintering machine embodying the improvements of the invention;

Fig. 2 is a cross-section taken on the line 2—2 of Fig. 1.

Like reference characters denote like parts in the two figures of the drawing.

In the drawing, 10 represents the pallets of an ordinary sintering machine of the straight-line or Dwight-Lloyd type, 12 the main windbox of the machine, and 14 the flue to the fan (not shown) which supplies the draft to the charge on the grates 16. The windbox 12 is supplied with the usual end walls 18, 20 and a bottom 22.

The side 24 of the windbox is shown as extending vertically down from the bed of the machine to a point below the flue 14 whence it is inclined inwardly, as indicated at 26.

5 A low side member 28 cooperates with the ends 18 and 20, bottom 22 and inclined side wall 26 to form a reservoir 30 in which water is maintained at the level indicated at 32. The side 34 of the windbox extends vertically from the bed of the machine to a point below the water level 32 but short of the bottom 22, all as indicated in Fig. 2. A water tank 36 supplied from a source 38 communicates with the bottom of reservoir 30 through conduit 40. A float and valve arrangement 42 controls the water level 32 in reservoir 30, as will be readily apparent from Fig. 2.

As the pallets 10 carry the material treated over the stationary windbox 12, particles carried into the latter through the grate bars 16 in response to the draft to which the charge 20 is subjected, will tend to accumulate in the pool of water 30. When sufficient dust particles, metallics, or the like, depending upon the particular material being treated on the grates, have accumulated sufficiently to warrant cleaning the windbox, a hoe, rake or similar implement is inserted in the space between members 28 and 34 and the material readily withdrawn under water from the interior of the windbox and out 25 along the inclined side member 28 of the trough or reservoir 30. Inasmuch as the windbox side wall 34 provides an air-tight seal between the enclosed and open portions of the reservoir 30, the draft in the windbox is nowise disturbed so that the windbox is readily cleaned without shutting down the operation of the machine.

While a specific construction has been shown in the drawing for purposes of illustration, it will be understood that various modifications and changes may be made within the spirit and scope of the invention. Thus, the invention may be readily adapted to circular sintering machines instead of the straight-line type illustrated. With either type of machine, changes in design of the windbox may be made to suit the particular use or sintering operation.

What is claimed is:

1. In metallurgical sintering machines of the down-draft conveyor type, the improvement which consists in providing a stationary windbox having a two-part trough which forms a reservoir for water in the bottom section of the windbox, said two-part trough having one part open to the surrounding atmosphere and arranged so that the reservoir in the bottom sec-

tion of the windbox is adapted to receive material falling from said conveyor, said trough providing a water seal in the bottom part of the windbox whereby the material falling into the trough may be removed without shutting down operation of the sintering machine by moving the material outwardly through said trough part which is open to the atmosphere, means for supplying water to said trough to form the reservoir and means comprising a float-operated valve for maintaining the water in said reservoir at the level required to provide a continuous water seal for said windbox.

2. In metallurgical sintering machines of the down-draft conveyor type, the improvement which consists in providing a stationary windbox having a trough in the bottom portion extending in the direction of the conveyor movement, means for supplying water to said trough, said trough of water being divided longitudinally by one of the side walls of the windbox, said trough dividing wall extending below the level of the water in the trough to provide a water seal in the lower part of the windbox but terminating a substantial distance above the bottom of said trough forming an outer trough portion which is open to the atmosphere, said open-trough portion providing a passageway through which material falling into the trough from the conveyor may

be removed without adversely affecting the normal draft on the sintering machine, by scraping it under said trough dividing wall into said open trough portion and up through the water over the rim of the trough, and means responsive to a lowering of the water level in the trough for maintaining the water seal in said windbox.

3. In metallurgical sintering machines of the down-draft conveyor type, the improvement which consists in providing a stationary windbox having a divided trough in its bottom section forming a reservoir for holding water, said trough being divided by a depending side wall of the windbox, said wall extending below the normal level of the water in the trough so as to form a liquid seal in the bottom part of the windbox, said wall terminating a substantial distance above the bottom of said trough providing a portion open to the atmosphere through which material falling into the trough from the conveyor can be removed without shutting down the machine by withdrawing it from under said depending wall and over the outer edge of the trough, means for supplying water to said trough and means comprising a float-actuated valve for keeping the water level in the trough normally such as to maintain the water seal continuously.

CHARLES H. HARRIS.
